TRAY TABLE

Walter W. Block, Kenosha, Wis., assignor to Quaker Stretcher Company, Kenosha, Wis., a corporation of Wisconsin

Application April 1, 1958, Serial No. 50,276

Term of patent 14 years

(Cl. D33—14)

Fig. 1 is a perspective view of a tray table showing my new design;

Fig. 2 is a side elevational view; and

Fig. 3 is an enlarged plan view thereof.

The dominant features of my design reside in the portions shown in full lines on the drawing.

I claim:

The ornamental design for a tray table, as shown and described.
